UNITED STATES PATENT OFFICE.

PIETER HONDIUS, OF Utrecht, NETHERLANDS.

PROCESS OF IMPREGNATING TOBACCO BY MEANS OF NATURAL OR ARTIFICIAL AROMATIC SUBSTANCES.

No. 858,289.

Specification of Letters Patent.

Patented June 25, 1907.

Application filed August 31, 1905. Serial No. 276,623.

To all whom it may concern:

Be it known that I, PIETER HONDIUS, agricultural chemist, a subject of the Queen of the Netherlands, residing at Utrecht, Buys 5 Ballotstraat 5bis, in the Kingdom of the Netherlands, have invented certain new and useful Improvements in Processes for the Impregnation of Tobacco by Means of Natural or Artificial Aromatic Substances or Organic Salts, of which the following is a full, clear, and exact description.

The quality and value of tobaccos depend upon their certain materials, which influence the burning of the tobacco and the color of 15 the ash.

I have found that the value of tobacco leaves can be favorably influenced by their impregnation with substances which are contained in superior kinds of tobacco and the 20 quality of inferior tobaccos can in this way therefore be raised to a higher value.

This invention consists in the method of improving the burning quality and flavor of 25 badly burning cigars by impregnating parts thereof with an extract of tobacco of good burning quality and of a flavor superior to that of the cigars treated.

In practice the following is the process used:—Waste cuttings of the leaves, stalks, 30 and ribs, or other residues of the tobacco factory, of good burning tobacco and tobaccos rich in organic salts, such as Deli-Langkat, 35 Sumatra, or the like, are used, and are soaked in water and the solution or extract obtained is concentrated by boiling, so that about a 10 per cent solution is obtained. The 10 per cent extract thus obtained then serves for 40 the impregnation of inferior-burning kinds of tobacco, such for example as Rio Grande, Java, Telock, Java, S. K., Deli and Slamat, Borneo. These last named kinds of tobacco 45 are those which are preferably to be treated according to the new process, but other kinds of tobacco of inferior burning quality can be very greatly improved by the use of the extract obtained in the way, and from the superior tobaccos above described. This improvement is effected by treating the inferior 50 kinds of tobacco named, for a certain time, for example, 24 hours, with a ten per cent solution of the extract which is prepared from good burning tobacco, as already mentioned. Cigars, the wrapping and covering

leaves of which have been impregnated in the way described, show, although made from inferior kinds of tobacco, the burning quality of the much superior kinds. According to the present invention, on the other hand, neither the addition of aromatic or like substances, nor the removal of the nicotin is the object desired. Generally it is not sufficient for the improvement of the burning of a cigar to effect the neutralization of the nicotin, as this is present especially in the inner part of or filling and any attempted improvement in the quality of the cigars themselves which may be made according to the processes heretofore employed, is not all aimed at in the present invention, in which the good-burning of the envelop or wrapping an outer covering is alone aimed at and effected. To improve in this way the burning of the cigar it is necessary, according to the process of the present invention to prepare an aqueous extract of the more or less waste parts of good-burning and more valuable kinds of tobacco, such as for example as Deli-Langkat, Sumatra, and others, as already referred to which after the removal of the substances injurious to the burning, such as albumen and the like, is treated by evaporation by heat, and the wrapping and the outer covering of the cigar of inferior kinds of tobacco are treated with a solution containing for example, about 10 per cent of the material thus extracted for a determined time, about 24 hours.

The most successful method for the preparation of the extract is carried out as follows:—An extract is made from cuttings of the leaves or other suitable parts of good burning tobacco, by means of water, and this extract is then concentrated by heat, the injurious inflammable substances such as albumen and the like being removed by drawing them off, skimming or filtering and the so-prepared extract is thickened by evaporation *in vacuo* until a viscous dark brown syrup containing crystals is obtained. By further inspissation a more or less solid greyish-white mass results, which like the syrup is easy to transport from place to place as required.

When required for use a suitable quantity of the syrup or product of the kind described is thinned down with water and the kinds of inferior burning tobacco to be treated are im-

pregnated with it for a sufficiently long time, for instance, for one day.

The details of the process may obviously be varied more or less.

5 What I claim is:

The method of improving the burning quality and flavor of badly burning cigars, consisting in impregnating parts thereof with an extract of tobacco of good burning

quality and of a flavor superior to that of the 10 cigars treated.

In witness whereof, I subscribe my signature, in presence of two witnesses.

PIETER HONDIUS.
